CLAIM

The ornamental design for a cake rack, as shown and described.

DESCRIPTION

FIG. 1 is an environmental perspective view of a cake rack showing my new design;

FIG. 2 is a perspective view thereof;

FIG. 3 is a top plan view thereof;

FIG. 4 is a bottom plan view thereof;

FIG. 5 is a front elevational view, the rear elevational view being a mirror image thereof; and,

FIG. 6 is a right side elevational view, the left side elevational view being a mirror image thereof.

The broken line showing of a person getting ready to put a Bundt cake into the cooling rack of my invention is for illustrative purposes only and forms no part of the claimed design.
